Nils H. Cederquist

By Fugit Moore
Attorney.

UNITED STATES PATENT OFFICE.

NILS HERMAN CEDERQUIST, OF LOS ANGELES, CALIFORNIA.

ADJUSTABLE PROPELLER FERRULE AND WOOD-HOLDING DEVICE.

Application filed May 3, 1922. Serial No. 558,291.

To all whom it may concern:

Be it known that NILS HERMAN CEDERQUIST, a citizen of the United States of America, residing at Los Angeles, in the county of Los Angeles and State of California, has invented certain new and useful Improvements in Adjustable Propeller Ferrule and Wood-Holding Devices, of which the following is a specification.

10 This invention relates to a bushing or the like for use in connection with propeller blades or other similar members subjected to a strain.

An important object of the invention is to 15 provide means for holding propeller blades or tips of any propeller of two or more pieces into the hub with a maximum factor of safety, and with a minimum possibility of shearing, twisting or breaking.

20 A further object of the invention is to provide a means for permanently or temporarily holding or removing propeller blades or tips into or from the hub or assembling said propeller blades or tips for 25 actual or experimental use without the aid of bolts, tubular wedges or other similar means employed by others, thus eliminating the weakening element ever present in the devices now used.

30 A still further object of the invention is to provide means for quickly replacing repaired parts or new blades to suit the experiment or tests to which any propeller blade or tip may be likely to be subjected, 35 with maximum factor for safety and with a great saving of time.

The purpose of my invention is to provide a holding device which can be manufactured at a very low cost and can be readily 40 applied.

My invention is unlike other blade holding devices because I believe I have solved the problem of securely holding the propeller tips of any two piece propeller in the hub, 45 with a maximum factor of safety, and with a minimum possibility of shearing, twisting or breaking. My invention altho simple, and constructed of only two parts consisting of a tubular ferrule and a spring like bushing is capable of withstanding the severest strain, and the greater the thrust the tighter the bushing fits within the ferrule. Moreover the device can be manufactured 50 at a small cost and much can be saved by

its use for various tests or replacing larger 55 or smaller blades or worn parts.

Other objects of the invention will be apparent during the course of the following description.

In the accompanying drawings, forming 60 a part of this specification and in which like numerals are employed to designate like parts through the same:

Figure 1 is a side elevation showing a propeller blade with ferrule and bushing 65 applied;

Figure 2 is a longitudinal sectional view of the ferrule and bushing assembled;

Figure 3 is a perspective view of the bushing showing its position before assemblage; 70 and

Figure 4 is a perspective view of the bushing member showing the shape assumed when applied.

As best illustrated in Figure 2 the letter 75 *c* designates a propeller blade the shank *s* of which is formed with a shoulder *d* for seating the substantially cone shaped bushing *a*. This bushing which, tapers inwardly allowing the tapered end *e* to rest on the said shoulder *d*, is made of flexible fibrous material snugly engaging the tapered shank *s* of the propeller blade. Surrounding the shank and sleeve is the tubular metallic ferrule *b* tapering from a given point on its inner side in an outwardly direction. The spring-like elasticity or flexibility of the bushing *a* is such that when the bushing is disassembled the small end *e* will be maintained in slightly open position, and the 85 large end *f* closed as shown in Figure 3. When subject to a slight pressure the jaws *g*—*g'* will be forced to closed or Figure 4 position.

To assemble the bushing all that is necessary is to force the bushing down over the propeller shank toward the blade end, the flexibility of the fibrous material of which the bushing is made permitting the jaws *g*—*g'* to spring open during this operation. As soon as the bushing seats on the shoulder *d* at *e* the ferrule is slipped over the blade end and moved in an opposite direction or away from the blade, under pressure of from fifteen to twenty five tons. This will 100 clamp the bushing tightly to the blade shank thus assuring a perfect alignment of blades and prevent shifting, shearing, twisting or 105

breaking. The ferrule is then threaded into the propeller hub (not shown). The centrifugal force exerted during rotation of the blades increases the wedging action between the parts, as will be readily understood.

It is to be understood that the form of the invention herewith shown and described is to be taken as a preferred example of the same, and that various changes in the shapes, size and arrangement of parts may be resorted to without departing from the spirit of the invention or the scope of the subjoined claims.

Having thus described my invention, what I claim is:

1. A wood holding device including a body member, a substantially cone shaped split bushing mounted thereon with its ends normally standing apart, and means mounted upon said bushing whereby to cause the edges thereof to move toward each other.
2. A device of the character described, comprising a propeller blade; a fibrous bushing split longitudinally, and a metallic ferrule mounted on said bushing, said ferrule having a beveled inner wall tapering

outwardly toward the hub end of the said blade.

3. A device of the character described, comprising a propeller blade; a fibrous bushing mounted on said blade, said bushing being split longitudinally and tapering toward the blade end of said propeller; a metallic ferrule mounted on said bushing, said ferrule having a beveled inner face thus providing an adjustable gripping surface.

4. A device of the character described, comprising a propeller blade; a fibrous spring-like bushing split longitudinally mounted on said blade; a metallic ferrule mounted on said bushing, said ferrule having a beveled inner wall tapering outwardly toward the hub end of the blade, said inner wall being adjacent the upper side of the bushing thus assuring a variable gripping force.

In testimony whereof I affix my signature in presence of two witnesses.

NILS HERMAN CEDERQUIST.
